M. E. Halsey.

Chair,

No 11,725.

Patented Sep. 26, 1854.

UNITED STATES PATENT OFFICE.

MOSES E. HALSEY, OF NEW YORK, N. Y.

CHAIR-FRAME.

Specification of Letters Patent No. 11,725, dated September 26, 1854.

To all whom it may concern.

Be it known that I, Moses E. HALSEY, of the city, county, and State of New York, have invented certain new and useful Improvements in the Construction of Chairs; and I do hereby declare that the following is a full, clear, and exact description of the same, reference being made to the annexed drawing, making a part of this specification, which is a view in perspective of a chair constructed according to my improvements.

My invention consists in so constructing the back of a chair that I am enabled to get the curves necessary to form an easy rest for the sitter and yet to have the grain of the wood lie in the several directions requisite to insure the greater strength the material is capable of affording. It is thus peculiarly applicable to "cottage chairs" or to those in which extreme delicacy of form and lightness are desirable features.

I make the posts in the common manner below the seat, but above that I carry them to only about one half the usual height, as at (a). Here they are secured by mortise and tenon, or other suitable devices, to two pieces (b) being supplementary posts which cross the upper ends of the first somewhat obliquely, and the lower ends of which are set in the back rail of the seat, as shown. The upper ends are curved inward and connected by a piece (c), forming a top rail. The short rail (d) completes the frame ready for the usual "cane." The piece (b) acts now as a lever upon

which the power is applied at the upper end, the fulcrum being at the point of connection with the post (a), and the resistance being at the lower end. At this part then the wood may be very light, and only so secured as to prevent those ends from moving forward. The grain of the posts (a) may now run nearly the entire length; while that of the pieces (b) may run in the direction of the length in that part of the pieces on which the greatest strain will come—that is—the central portion. This mode of construction effects a great saving of material, since all the parts, curved to the easiest possible form, can be cut from a short plank of one and a half inches in thickness and eight inches in width, while the same curves would require in common construction timber of eight inches square, and of the entire length of the chair, and would then be deficient in strength from the necessary direction of the grain in those parts where the maximum is required.

What I claim as my invention and desire to secure by Letters Patent is—

The construction of the back of a chair in the manner described—that is to say—combining with each post, and with the back rail of the seat, a supplementary post sustained and braced substantially in the manner and for the purpose set forth.

M. E. HALSEY.
